UNITED STATES PATENT OFFICE.

WILLIAM F. FREEMAN AND VRL ITHIEL CILLEY, OF GRAND RAPIDS, MICHIGAN.

DIRECTION INDICATOR.

1,422,955.

Specification of Letters Patent.

Patented July 18, 1922.

Application filed October 2, 1920. Serial No. 414,297.

To all whom it may concern:

Be it known that we, WILLIAM F. FREEMAN and VRL I. CILLEY, citizens of the United States, residing at Grand Rapids, in the county of Kent and State of Michigan, have invented certain new and useful Improvements in Direction Indicators, of which the following is a specification.

Our invention relates to improvements in direction indicators for use upon automobiles, and kindred vehicles, and its objects are: first, to provide a means whereby a signal having a revoluble cylinder therein with several indicating symbols thereon, may be operated directly from the brake rod of the vehicle to actuate the cylinder to exhibit the danger signal and the stop signal with but a slight movement of the brake rod without danger of revolving the cylinder further with further longitudinal movement of the brake rod; second, to provide a means, independently of the brake rod or brake mechanism, whereby these, and additional signal symbols may be exhibited; third, to provide a means whereby the revoluble movements of the cylinder may be readily regulated to properly exhibit the several symbols; fourth, to provide a means whereby the sudden stopping of the cylinder and other several elements in the indicator may be accomplished without metallic sounds or poundings; fifth, to provide a means whereby the cylinder and its supporting frame may be readily placed into, and removed from the indicator case; sixth, to provide a means whereby rays of light from the interior of the cylinder will be prevented from shining or passing through between the edges of two cylinder panels to the transparent panel in the indicator case, and, seventh, to provide a means whereby the actuating cable may be protected, first, from corrosion by exposure to the weather, and, second, from rapid erosion from friction upon its supporting elements.

We attain these objects by the mechanism and arrangement of parts shown in the accompanying drawing, in which Fig. 1 is a longitudinal sectional elevation of the case and cylinder, showing the relative positions of the several elements of our invention. Fig. 2 is an elevation of the, relatively, right hand end of the indicator with the end cap removed to show the relative positions of

the several elements for actuating the cylinder. Fig. 3 is a sectional elevation of the other end of the case showing the manner of constructing the cylinder frame. Fig. 4 is a front elevation of the cylinder frame. Fig. 5 is a sectional elevation of a part of an automobile body showing the relative positions, and the applications of the several parts of our invention with the indicator case, and the flexible enclosing tube for the actuating cable, considerably exaggerated in size to make their application and operation more clear than if shown upon a uniform scale with the automobile body. Fig. 6 is an elevation of the, relatively, left hand end of the indicator case with the end cap removed to show the several elements placed upon this end of the indicator. Fig. 7 is a side elevation of one of the cylinder reels or spools showing its stop, or bumper pad. Fig. 8 is an edge view of the bumper support showing means for supporting the other bumper element. Fig. 9 is an elevation of the control case with the back removed to show the relative positions of its several elements. Fig. 10 is an edge view of the same, and, Fig. 11 is a back view of the same.

Similar reference characters indicate similar parts throughout the several views.

In the accompanying drawing, 1 represents the indicator case; 2 is the end cap of the case. In the construction of the case we depress the ends, at 3 so as to form a close frictional bearing between the ends of the case and the flanges on the end caps 2, as at 4 securing the cap thereto in such a manner that it, or they, may be readily removed. In this construction the cylinder is composed of four panels 6, (more or less) mounted upon the edges of the ends 9, which are provided with flanges 9'. The ends 9 are provided with cylindrical bearings 8, 8', the former being designed to revolve freely within the openings formed by the flanges 14 on the frame ends 5, and the latter are designed to pass snugly into the flanged bearing 9' in the cylinder ends. The panels 6 are made of sheet metal and have indicating symbols, as 7, made therein.

The cylinder is mounted in a frame composed of the ends 5 supported by the girts 15 and 16, and so made that it can be read-

ily placed into the case 1 and be held securely by friction at 4, and may be readily removed from the case, when desired.

In carrying out our invention, we mount 5 an antifriction roller 11 upon the spool rim 10, arranged to stand normally, directly at the upper edge of the spool. We then mount a cam arm 12, pivotally, upon the frame end 5, as at 24, the normally lower end of 10 the arm being provided with a hub 13, and the upper end having the cam 12' formed thereon in such a position that if the arm is drawn, relatively, to the right, as in Fig. 2, the cam will contact the antifriction 15 roller 11 and will carry the cylinder one quarter of a revolution, as indicated at 17', as soon as the cam has been moved far enough to carry its inclined end off of the roller, and the balance of the travel, if any, 20 of the cam will not disturb the position of the cylinder. To actuate the cylinder in this instance, the cable 22, is passed through the flexible tube 21, and one end thereof is securely connected with the hub 13, the other 25 end being secured to the brake rod 31, as at 23, so that the first slight movement of the brake lever 17 will move the cam arm, and the cylinder, as hereinbefore described, moving the cylinder from its normal position, 30 say to exhibit an ordinary tail light, one quarter of a revolution to exhibit, say, the word "Stop," these being presumed to be the two essential signals and, necessarily, demanding actual automatic action.

35 In this instance we have indicated a cylinder with four sides, hence four indicating symbols. Having intimated the nature of the essential signals, we will presume that the other two signals comprise a right hand, 40 and a left hand indicating symbol, as arrows, indicated at 7. To actuate the cylinder to exhibit these symbols independently of the brake mechanism, we secure a second flexible tube, 19, (or preferably so) to the 45 end of the indicator, as with the clamping plates 18, and pass a metal cable 20 through this tube with one end passed around the hub 8 of one of the spools on the cylinder and secure it thereto, so that if the cable 20 is drawn upon it will cause the cylinder to 50 revolve proportionately. We prefer that the flexible tube 19 extend from the indicator case the entire distance to the element by which it is controlled, but this is not essentially necessary. The other end of the cable 55 is connected with some available form of control, as, for instance, the control shown at 30, mounted upon the steering post 29.

This control consists of a containing case 60 30 that is securely clamped upon the steering post 29, as indicated in Fig. 9. In this case is revolvably mounted a cylindrical hub 32, the flexible tube being secured to the case as at c and the cable 20 is passed through the 65 rim of the cylinder, as at C, and is secured

to the stud 36 in such a manner that should the cable stretch slightly, or, for any other reason, need adjustment, this can be attained by turning the stud around and winding the cable around it, as indicated in Fig. 9. This 70 stud is secured into the case in such a manner that it may be readily revolved, but will be held securely in place, against the natural strain of the cable, so that no matter where it is set, it will remain stationary and hold the cable in the exact desired position. We secure a lever 33 to the cylinder 32 and pass it through the slot A in the case 30. To insure the proper 75 exposition of the arrow symbols we form a stop at a, and another at b, so that when the lever 33 is carried to the position indicated at a' one arrow as the right indicating arrow, will be exposed, and if the lever is carried to b' the other arrow, as the left indicating arrow will be exposed.

A very objectionable feature present in indicators having revoluble cylinders is the fact that when the cylinder is suddenly revolved to its extreme limit, whether forwardly or backwardly, metal coming in contact with metal will produce a very loud, rattling metallic sound, and to obviate this we have placed a supporting element, as the arm 27 upon the end of the cylinder frame. 90 and to this we have secured a leather bumper 28, or its equivalent, and have placed a corresponding securing plate 25, and bumper 26 upon the flange 10 of the spool 8 in such positions that when the cylinder is carried 95 to its extreme limit of travel these bumpers will be in contact, and no matter how forcibly the contact may be brought about the sudden contact of the soft material will give off, comparatively, no sound. We bring 100 about the same results by forming a slot, 35, in the body of the cylinder 30, with the ends projecting at right angles, as at d, and placing a bumper 34, of some soft material, as leather, etc., securely upon the cylinder back, as shown in Fig. 9 and indicated in Fig. 11 of the drawing. We sometimes provide, also, for regulating the movements of the lever 33 by placing an adjustable plate 37 upon the rim of the case 30 110 immediately at the lower end of the slot A, that may be over the end of the slot if necessary, but prefer the use of the stud 35 for this purpose.

At 38 we have shown how the two sides 120 of the control case may be held securely in place together, by means of a single screw passed through one of the plates and screwed into the supporting stud 39.

It is to be understood that the cylinder 125 is always revolved back into normal position by means of a properly adjusted spring, as indicated at 40.

One of the prime advantages attained by this construction of the cylinder frame, is 130

that it may be used, within the body of the automobile without any enclosing case, by simply anchoring it within the car at the desired place, and cutting a suitable opening 5 through the car for the passage of light and the exhibit of the symbols. This is particularly advantageous where the indicators are to be made a part of the standard equipment of the automobile in the process of 10 manufacturing the automobiles, or other vehicles.

When the cylinder in this indicator stands in its normal position an ordinary tail light with, perhaps, some ornamental symbols, will 15 be exhibited through the front opening of the case. When revolved into second position the word "Stop" or its equivalent, will be exhibited. When revolved into third and 20 fourth positions, respectively, a right hand pointing arrow, or a left hand pointing arrow will be exhibited, etc., hence these terms will be used to designate the several positions, in the claims.

Having thus fully described our invention, what we claim as new in the art, is:

1. In combination with a direction indicator having a revoluble symbol cylinder therein; an antifriction roller revolubly mounted upon one end of the cylinder, a 30 cam arm pivotally mounted, at one end, upon the end of the cylinder frame, a cam mounted on the other end of the arm in position to engage the antifriction roller and revolve the cylinder from first position into second 35 position, and means for connecting the cam arm with the brake rod of an automobile.

2. In combination with a revoluble direction indicator, a frame for supporting the revoluble cylinder, and bearings at the ends 40 of the cylinder in the ends of the frame, said bearings having flanges thereon, an antifriction roller revolubly mounted upon one of the flanges, a cam arm pivotally mounted at one end upon the end of the cylinder frame, 45 a cam upon the other end of the cam arm so formed that first contact with the antifriction roller will revolve the cylinder from first position into second position and that further movement of the cam in the same 50 direction will not affect the position of the cylinder, a flexible tube mounted upon the frame, a cable slidingly mounted in the tube with one end connected with the cam arm and the other end connected with the brake 55 rod of an automobile in such a manner that the first movement of the brake rod forwardly will revolve the cylinder from first position into second position and further movement of the brake rod will not change 60 the position of the cylinder though changing the positions of the cam and of the cable.

3. In combination with a direction indicator having a revoluble symbol cylinder with several distinct symbols therein, a skele- 65 ton frame for carrying the cylinder, an anti-

friction bearing upon one end of the cylinder outside of the frame, a cam arm mounted upon the end of the frame a cam upon said arm in position to engage the antifriction bearing on the cylinder, means for actuating 70 the cam arm and cam from the brake mechanism of an automobile to revolve the cylinder from first position into second position with the first forward movement of the brake lever, means for holding the cylinder steadily in second position during the further forward movements of the brake lever, means independently of the brake mechanism for revolving the cylinder into third position, 75 fourth position, or other desired positions, and means for returning the cylinder into normal position when released.

4. In combination with an automobile direction indicator having a revoluble symbol cylinder therein, an enclosing case having a front opening therein, arranged to exhibit several distinct symbols through the one opening in the case, a skeleton frame for revolubly supporting the cylinder at each end thereof, means connected with one end 90 of the cylinder frame and with the cylinder and the brake mechanism whereby the cylinder will be made to revolve from first position into second position with the first forward movement of the brake mechanism and 95 will remain stationary during further forward movement of the brake mechanism, means connected with the end of the cylinder for moving the cylinder into further successive positions independently of the 100 brake mechanism, a stationary light within the cylinder, means for returning the cylinder into normal position when released by the actuating mechanism, and means for rendering the stopping of the cylinder 105 noiseless.

5. The combination with a direction indicator having a supporting case with a display opening therein, a symbol cylinder revolubly mounted within the case, means 110 connecting the cylinder with the brake mechanism of an automobile in such a manner that the first forward movement of the brake rod will revolve the cylinder from first position one quarter of a revolution 115 into second position and hold it permanently during further forward movement, and the first backward movement of the brake rod will allow the cylinder to return into normal position, means independent of 120 the brake mechanism for revolving the cylinder into other predetermined positions independently of the brake mechanisms, and means for returning the cylinder automatically into normal position when released by 125 the actuating mechanism, and so arranged that the several signal symbols may be successively or individually displayed through the one opening in the front of the case.

6. In combination with the mechanism 130

covered in claim 3, an arm secured at one end to the end of the cylinder frame, the other end of this arm extending upwardly and offset to pass over the end of the cylinder, a soft buffer element secured to the upper end of said post, and a soft buffer element secured to the end of the cylinder in position to engage the buffer element on

the arm at each end of the revolvel movements of the cylinder and deaden the sound of forcible contact between the arm and cylinder end.

Signed at Grand Rapids, Michigan, September 24, 1920.

WILLIAM F. FREEMAN.
VRL ITHIEL CILLEY.
